A. J. PETERSON ET AL.

LAUNDRY WRINGER

Filed Dec. 11, 1922

UNITED STATES PATENT OFFICE.

ARTHUR J. PETERSON AND ROY E. MELVIN, OF CHICAGO, ILLINOIS, ASSIGNEES, BY
MESNE ASSIGNMENTS, TO APEX PRODUCTS COMPANY, A CORPORATION OF ILLI-
NOIS.

LAUNDRY WRINGER.

Application filed December 11, 1922. Serial No. 606,247.

To all whom it may concern:

Be it known that we, ARTHUR J. PETERSON and Roy E. MELVIN, citizens of the United States, all residing at Chicago, in the county 5 of Cook and State of Illinois, have invented certain new and useful Improvements in Laundry Wringers, of which the following is a specification.

This invention relates to laundry wringers.

One of the objects of the invention is to simplify and cheapen the cost of construction of wringers.

A further object is to provide a wringer 15 in which the parts may easily be assembled.

A further object is the provision of simplified means for independently tensioning the rollers.

Another object is the provision of effective and simplified means for releasing the 20 spring tension on the rollers.

Another object is the provision of a frame in which relatively long compression springs are used to permit increase in the latitude 25 of relative movement of the rollers and which springs are arranged for coincident adjustment and simultaneous release.

Another object is to provide a safety release whereby the tension effect of the 30 springs may instantly be removed from the rollers by a very small movement of an accessible lever.

Another object is to provide a frame which completely encloses all of the working parts 35 of the wringer except the working surfaces of the rollers.

Another object is generally to improve wringers.

Other objects and advantages will be 40 become readily apparent to persons skilled in the art from a consideration of the specification when taken in conjunction with the drawings, made a part hereof, and in which

Fig. 1 is a side elevation of the wringer 45 with one portion of the frame removed.

Fig. 2 is a section taken on line 2—2 of Fig. 1 when both members of the frame are in place.

Fig. 3 is a section taken on line 3—3 of 50 Fig. 1.

Fig. 4 is an enlarged section taken on line 4—4 of Fig. 1.

Fig. 5 is an isometric perspective view of one of the bearing blocks in which the lower roller is journaled.

In all the views the same reference characters are used to indicate corresponding parts.

The frame comprises two major members or parts A and B, the latter is hinged to the former at 10—10'. The major portion A of the frame may be connected to an angle bar support 11 by bolts 12. Each frame member has two depending legs 13—13' and 14—14', respectively. The two parts A and B of the frame are held in connected relation by bolts 15.

Each frame member including its legs are hollow and each member carries part of a gear housing 16—16', respectively, and this housing is extended on each member to include portions 17 to overlie one end of both rollers. Another similar roller housing 18 is a part of each frame member and overlies the other ends of the rollers. These 75 housings 17—18 prevent access to the ends of the rollers and serve as guards to prevent fabric from winding around the shafts upon which the rollers are mounted.

Roller 19 is journaled in bearing blocks 20—20' and is relatively fixed in position. The journal 21 upon which the roller 19 is mounted carries on one end a clutch member 22 for driving connection with the clutch member 23. The other end of the shaft 21 projects into the gear casings 16—16' and carries a toothed pinion 24 for meshing relation with toothed pinion 25 which is also in the gear casing and which is secured to the shaft 26 upon which the roller 27 is mounted. The shaft 26 is journaled in rectangular bearing blocks 28—28' at its respective ends and these are within the walls of the frame. The downward movement of the bearing blocks 28—28' is limited only by contact of the rollers 19 and 27, one with the other.

The blocks 28—28' are guided within the ends of the frame members by side walls 29—29' and by the stiffening ribs 30 and end 100

walls 31. The ribs 30 extend to the shaft 26 on each side, so that the shaft and its roller may freely be moved vertically with its bearing blocks enclosed within the guide walls.

A chamber 32 is jointly provided in the frame members above the rollers 19-27. In this chamber a floating bar 33 is located. It has perforated, bifurcated ends having members 34-34' at each end. Pivoted between the members 34-34', as at 35, is a lever 36-36' having a down-turned end 37 which rests, at each end of the bar, upon the top of the journal blocks 28-28', respectively. The levers 36-36' each have an up-turned end 38, pivoted to a spring guiding block 39, at 40. The blocks 39 engage the outer ends of the open compression springs 41-41', respectively. The inner ends of the springs bear against abutments 42-42', which rise from the bar 33 and which are, preferably, integral parts thereof.

When the bar 33 is depressed the up-standing members 38 of the levers 36-36' are moved inwardly, whereupon the springs 41-41' are thereby compressed and the rollers 27 and 19 are more intimately brought into contact.

A block 43 extends outwardly thru the walls 31-31' of the frame members, carries a plate 44 which can not pass thru the openings in the walls 31-31', and is formed at its lower end into two oppositely disposed tapered and curved cams 45 and 46, the higher part and the lower part of each cam terminates in a slot 47.

An internally threaded tube 48 passes thru the part 43 and is provided with a cross bar 49 secured to its upper end by which to rotate the tube. Secured to the tube, or integral parts thereof, are lugs 50-50' which ride upon the cams 45 and 46, respectively, and which enter the slots 47 as the tube is rotated by the cross bar.

Threaded into the tube 48 is a stem 51, provided with a hand wheel 52 fixed to its upper end, the lower end of which passes thru a stirrup 53 fixed to the bar 33 to hold the latter in place. By means of the threaded stem 51 the bar 33 may be depressed to tension the springs 41-41'. The springs when stressed tend to lift the bar 33 by the end 37 of the lever 36 acting as a fulcrum and yieldingly holding the bearing blocks 28-28' and the roller 27 depressed when the bar cannot be raised, therefore the further the bar is depressed by the threaded stem 51, the greater will the springs 41-41' be tensioned and the rollers are thereby more firmly held together. This tension on the rollers may quickly be released by rotating the cross bar 49 until the lugs 50-50' drop off the cams 45-46 into the slots 47, whereupon the bar 33 will be released and will be

moved upwardly by the springs, and thus the upper roller 27 may be moved upwardly substantially out of stressed contact with the roller 19 as the stress to hold them together has now been removed.

The cross bar 49 serves as a safety means to quickly remove the stress of the springs upon the rollers and, furthermore, it is a convenient means for this purpose supplemental to the operation of the threaded stem 51. The desired tension of the springs may be adjustably obtained by rotation of the hand wheel 52 and after being released by the bar 49 it may again be established by further rotation of the bar without again adjusting the hand wheel.

When the frame members A and B are separated, all of the mechanism may be placed in position in one frame member and the members then placed together and held by the bolts 15. The frame members may be punched and formed of sheet metal or they may be made in form of castings.

A drip board 53 is placed over pins 54, which support it, and on its under face it has hooks 55 which limit its movement below the rollers, and permit it to assume an inclined position on either side of the rollers when it is shifted.

Having described our invention, what we claim as new and desire to secure by Letters Patent, is:—

1. In a wringer two like hollow separable frame members, each member having a pair of legs hinged together at the lower ends of the legs; means to hold the frame members together and roller controlling mechanism enclosed between the walls of the frame members and bodily removable therefrom as an operative unit.

2. A wringer having a pair of relatively movable rolls geared together in combination with a hollow wringer frame comprising two like separable members enclosing two vertical chambers and a communicating transverse horizontal chamber; roll bearing members in each vertical chamber, one pair of which is vertically movable and guided in their movement by the side walls of the frame; a pair of springs in the transverse chamber; connections between the springs and the movable bearing members, respectively independently of the frame, and means outside of the frame casing for varying the tension of the springs.

3. A wringer having a pair of relatively movable rolls geared together in combination with a bar substantially parallel with the axes of the rolls; a bell crank pivoted to each end of the bar independently of the frame, one end of each crank arranged to depress one roll; the other end of each crank abutting and open compression spring; and abutment near the center of the

bar against which the adjacent ends of the springs bear and means to depress the bar to tension the springs.

4. A wringer having a pair of relatively movable rolls geared together in combination with a bar substantially parallel with the axes of the rolls; a bell crank pivoted to each end of the bar, one end of each crank arranged to depress one roll; the other end 10 of each crank abutting an open compression spring; an abutment near the center of the bar and provided by the bar against which the adjacent ends of the springs bear; adjustable means to depress the bar to tension 15 the springs and means to quickly release the bar without disturbing the spring adjustment.

5. A wringer having a hollow frame; a pair of rollers therein, the upper one of which is 20 vertically movable; a slideable bearing block at each end of the movable roller; guides for the bearing blocks provided by the walls of the frame; a vertically movable bar parallel with the axes of the rollers; a bell crank 25 pivoted to each end of the bar and independently of the frame, a downwardly extending end resting on the respective bearing block; an abutment provided by the bar near the center of the bar; an open helical spring on 30 each side of the abutment having their adjacent ends bearing against said abutment

and its remote end against the upstanding arm of the respective bell crank lever; means to adjustably depress the bar to tension the springs and means to release the bar and 35 permit the springs to relax.

6. A wringer having a hollow frame; a pair of rollers, the upper one of which is vertically movable; a slideable bearing block at each end of the movable roller; guides 40 for the bearing blocks provided by the side walls of the frame; a vertically movable bar parallel with the axes of the rollers; a bell crank pivoted to each end of the bar and independently of the frame, a downwardly extending end resting on the respective bearing block; an abutment provided by the bar near the center of the bar; an open helical spring on 45 each side of the abutment having their adjacent ends bearing against said abutment and its remote end against the upstanding arm of the respective bell crank lever; a screw to adjustably depress the bar to tension the springs and a cam structure having a member rotatable 50 to release the bar and permit the springs to relax.

In testimony whereof we hereunto set our hands.

ARTHUR J. PETERSON.
ROY E. MELVIN.
